UNITED STATES PATENT OFFICE.

HORACE C. NICHOLS, OF BROOKLINE, MASSACHUSETTS.

DESIGN FOR A COMBINATION SINK AND TRAY BRACKET.

46,136.

Specification for Design.

Patented July 21, 1914.

Application filed April 17, 1914. Serial No. 832,644. Term of patent 3½ years.

To all whom it may concern:

Be it known that I, HORACE C. NICHOLS, a citizen of the United States, residing at Brookline, in the county of Norfolk and Commonwealth of Massachusetts, have invented a new, original, and ornamental Design for a Combination Sink and Tray Bracket, of which the following is a specification, reference being had to the accompanying drawing, forming a part thereof.

In the drawing, the figure is a perspective view showing the invention.

I claim—

The ornamental design for a combination sink and tray bracket as shown.

HORACE C. NICHOLS.
